UNITED STATES PATENT OFFICE

PHILIP A. MICHELL, OF NEW BRIGHTON, NEW YORK, ASSIGNOR TO BRANDES LABORATORIES, INC., OF NEWARK, NEW JERSEY, A CORPORATION OF NEW JERSEY

ACOUSTIC DEVICE

Application filed April 26, 1929. Serial No. 358,216.

My invention relates broadly to electromagnetic sound reproducers and more particularly to a construction of drive pin mounting for electromagnetic sound reproducers.

5 One of the objects of my invention is to provide a construction of magnetic driver for sound reproducers in which a drive pin is employed to transfer vibrations from an armature member to a sound reproducing diaphragm with means for limiting the whipping action of the drive pin.

Another object of my invention is to provide means for controlling the movement of the drive pin in a magnetic type of sound 15 reproducer for preventing rattling and other noises in sound reproduction.

Still another object of my invention is to provide a construction of suspension member for the drive pin for avoiding the setting 20 up of rattling noises in the sound reproducer system.

A further object of my invention is to provide a sheet metal member which may be supported upon an electromagnetic driving system of a sound reproducer for suspending the drive rod of the sound reproducer while limiting the whipping action thereof and preventing excessive vibration of the sound reproducing diaphragm to which the drive 25 rod is connected.

Other and further objects of my invention reside in the construction of suspending member for the drive pin of an electromagnetic sound reproducer as set forth more clearly 35 in the specification hereinafter following by reference to the accompanying drawings, in which:

Figure 1 is a side elevation with parts partially broken away and parts shown in cross-section for illustrating the arrangement of 40 the electromagnetic speaker system; Fig. 2 is a plan view of the electromagnetic driving mechanism and suspension for the sound reproducing diaphragm set forth in Fig. 1; Fig. 3 is a front view of the drive pin mounting member of my invention; Fig. 4 is a cross-sectional view through the drive pin mounting member illustrated in Fig. 3 on line 45 4-4 thereof; Fig. 5 is a lateral cross-sectional view through the drive pin mount- 50

ing member taken on line 5-5 of Fig. 3; Fig. 6 is a side elevation of a modified form of drive pin mounting embodying the principles of my invention; Fig. 7 is a plan view of the modified form of drive pin mounting illustrated in Fig. 6; Fig. 8 is a front view of the drive pin mounting shown in Figs. 6 and 7; Fig. 9 is a cross-sectional view of the construction of drive pin mounting illustrated in Fig. 8 taken on line 9-9 thereof; Fig. 10 is a lateral cross-sectional view through the drive pin mounting of Figs. 8 and 9 on line 10-10 of Fig. 8.

In electromagnetic sound reproducers employing a conical shaped sound reproducing diaphragm, I have found that excessive whipping action of the sound reproducing diaphragm introduces rattles and other noises in the sound reproducing system which tend to detract from the enjoyable qualities 65 of music or sound which is being reproduced. In conical shaped sound reproducing diaphragms, the whipping action which occurs as a result of excessive movement of the drive pin which interconnects the vibrating armature member with the apex of the cone tends 70 to produce rattling of the diaphragm which impairs the quality of the reproduced sound. I have found that highly desirable results 75 are obtained in sound reproduction where 80 means are provided for suspending the drive pin which interconnects the moving armature with the conical shaped sound reproducer in such manner that the armature member is normally maintained centrally of the 85 electromagnetic driving system, and excessive movement of the drive pin prevented by 90 a balanced system of forces which becomes effective when the drive pin tends to exceed a predetermined amplitude of movement required for the proper reproduction of sound.

The double lever arrangement of the suspension means which I employ in mounting the drive pin as set forth in the drawings herein has been found to be highly practical 95 in its construction and successful in its operation in eliminating whipping action of the drive pin with inherent noise disturbances.

Referring to the drawings in detail, reference character 1 designates a permanent mag-

net which may be of the horseshoe type having poles 2 and 3. Reference character 4 designates a similar permanent magnet having poles 5 and 6 which are clamped on opposite sides of the supporting member 7 by means of bolts 35 and 36 which pass through pole pieces 14 and 15 and through supporting plate members 16 and 17, which provide means for mounting the electromagnetic system. The electromagnetic driving system is mounted upon the portion 8 of member 7 and supported by means of a plate 9 and a series of plate members 11 which are adjustable in position with respect to member 8 by adjusting screws 13. Electromagnetic winding 12 is wound upon bobbin 10 which is apertured at 18 to receive armature member 20 which is centrally pivoted within the winding. A drive pin 19 extends from armature 20 and is supported at its outer extremity by means of the double lever formed by strip 22. The strip 22 is secured to one end of the member 7 and is bent upon itself as indicated at 23 extending in a plane parallel to the portion 22 as represented at 24. The portion of the strip 22 is strengthened by means of ribs 27 pressed in the face of the strip. The portion 24 is strengthened by means of ribs 25. An aperture 26 is formed in the strip 22 to permit the passage of drive rod 19 therethrough. The end of drive rod 19 is secured in the extremity of portion 24 of strip member 22 by means of solder or clamps, or in some other suitable manner. The conical shaped sound reproducing diaphragm 28 is secured to the drive pin 19 by means of clamping nuts 29 and 30 which grip opposite sides of the apex of the sound reproducing diaphragm.

Instead of providing a return bend strip for suspending the drive pin 19, I may press the suspension strip from a flat sheet of material which I have represented in Figs. 6 to 10 where the strip 38 is apertured at 32 with a tongue 33 struck out therefrom and extending in a plane parallel to the plane of strip 38, but offset therefrom. The strip 38 is reenforced by means of ribs 31 formed adjacent the edges thereof. The tongue 33 is reenforced by means of ribs 34 formed adjacent the edges thereof. The drive pin 19 is anchored in the extremity of the tongue 33.

Referring to Figs. 4 and 9, the forces which are set up under the action of the vibrating armature 20 have their direction indicated by arrows 39 and 40. That is, the portions of the suspension member 22 or 38 are free to move relative to each other in a rolling or rocking action which is free of whipping action by virtue of the normal resiliency of the parts of the suspension device. Any tendency of the portion 24 to move toward the plate 22 or the tongue 33 to move toward the plate 38 is resisted by a restoring force

due to the natural resiliency of the suspension device.

I have found that the forces incident upon the suspension strip tend to balance the movement of the drive pin exercising the required counteracting forces to prevent angular movement of said pin in such manner that whipping action is eliminated.

While I have described preferred embodiments of my invention, I desire that it be understood that modifications may be made and that no limitations upon my invention are intended other than are imposed by the scope of the appended claims.

What I claim as new and desire to secure by Letters Patent of the United States is as follows:

1. In an electromagnetic sound reproducer, a vibratory armature member, a sound reproducing diaphragm, a drive pin interconnecting said armature member with said sound reproducing diaphragm, and means for suspending said drive pin comprising a resilient strip of material bent upon itself, said drive pin passing through one portion of said resilient strip and being connected to another portion thereof.

2. In an electromagnetic sound reproducer, a vibratory armature member, a sound reproducing diaphragm, a drive pin interconnecting said armature member with said sound reproducing diaphragm, and suspension means for said drive pin, said suspension means comprising a strip of material having a pair of parallel extending portions with one of said parallel extending portions secured to said drive pin, and the other of said parallel extending portions apertured to permit the passage of said drive pin therethrough for connection to the first mentioned portion of said strip.

3. In an electromagnetic sound reproducer, a vibratory armature member, a sound reproducing diaphragm, a drive pin interconnecting said armature member with said sound reproducing diaphragm, and suspension means for said drive pin comprising a resilient strip of material permanently supported at one end and connected at the other end with a portion of said drive pin, said strip being bent upon itself and apertured in one portion thereof to permit the passage of said drive pin therethrough for connection to the end of said strip.

4. In an electromagnetic sound reproducer, a vibratory armature member, a sound reproducing diaphragm, a drive pin interconnecting said armature member with said sound reproducing diaphragm, and suspension means in said drive pin comprising a resilient strip having portions thereof lying in separate parallel planes, means for reenforcing each portion of said strip, one portion of said strip being connected to said drive pin, the other portion of said strip be-

ing apertured for the passage of said drive pin therethrough, the portions of said strip being relatively movable for controlling the movement of said drive pin.

5. In an electromagnetic sound reproducer, a vibratory armature member, a sound reproducing diaphragm, a drive pin interconnecting said armature member with said sound reproducing diaphragm, and suspension means for said drive pin comprising a resilient member having a plurality of relatively movable parts, a connection between one of said relatively movable parts and said drive pin intermediate the ends of said drive 10 pin, said resilient member being apertured in another portion thereof for the passage of said drive pin therethrough, for connection to the first mentioned portion of said resilient strip whereby excessive movement of said 15 drive pin is eliminated.

PHILIP A. MICHELL.
